UNITED STATES PATENT OFFICE

117,487

DESIGN FOR A COMBINATION SOAP DISH AND BRACKETS

Roy S. Sanford, Oakville, Conn., assignor to The
Autoyre Company, Incorporated, Oakville,
Conn., a corporation of Connecticut

Application August 2, 1939, Serial No. 86,409

Term of patent 7 years

To all whom it may concern:

Be it known that I, Roy S. Sanford, a citizen of the United States, residing at Oakville, in the county of Litchfield and State of Connecticut, have invented a new, original, and ornamental Design for a Combination Soap Dish and Brackets, of which the following is a specification, reference being had to the accompanying drawing, forming a part thereof.

Figure 1 is a perspective view of a combination soap dish and brackets, showing my new design;

Fig. 2 is a front elevational view of Fig. 1; and
Fig. 3 is a side elevational view of Fig. 1.

The essential features of my design reside in a soap dish of the configuration shown in combination with a pair of spaced brackets, substantially as illustrated in the drawing.

I claim:

The ornamental design for a combination soap dish and brackets, substantially as shown and described.

ROY S. SANFORD.
